UNITED STATES PATENT OFFICE.

GEORGE N. DAMON, OF LORAIN, OHIO, ASSIGNOR TO THE LORAIN RUBBER HEEL COMPANY, OF LORAIN, OHIO, A CORPORATION OF OHIO.

RUBBER HEEL AND INSERT THEREFOR.

1,387,243.

Specification of Letters Patent.

Patented Aug. 9, 1921.

Application filed January 7, 1920. Serial No. 349,970.

To all whom it may concern:

Be it known that I, GEORGE N. DAMON, a citizen of the United States, residing at 360 Washington avenue, Lorain, in the 5 county of Lorain and State of Ohio, have invented certain new and useful Improvements in Rubber Heels and Inserts Therefor, of which the following is a specification.

This invention relates to resilient heels for 10 shoes or other articles of footwear.

The object of the invention is to provide an improved heel of cushion form designed to soften the blow of impact with the pavement and which is equipped with an improved 15 wear resisting member or element of simple form which can be made and embedded in the heel by simple operations and at low cost, and which member is firmly anchored and not liable to pull out of place 20 and which greatly increases the life of the heel. A further object of the invention is to provide a wear resisting member or element of special form and configuration for 25 the purposes before stated.

Further objects of the invention are in 30 part obvious and in part will appear more in detail hereinafter.

The invention comprises the construction and arrangement of parts hereinafter described and claimed.

In the drawings, Figure 1 is a bottom plan view of a heel embodying the invention; Fig. 2 is a top plan view; Fig. 3 is a detail sectional elevation on the line 3—3, 35 Fig. 1; Fig. 4 is a plan view of the wear resisting member; Fig. 5 is a side elevation thereof; and Fig. 6 is a plan view illustrating the manufacture of the wear resisting element.

The heel forming the subject matter of the present invention is in large measure an improvement upon the heel described, shown and claimed in the Patent No. 1,193,198, granted August 1, 1916, to J. Solomon. It 40 comprises the body portion 1 formed of rubber or other suitable resilient material having a bottom tread portion 2 and an upper portion 3 designed for application to the shoe heel. This upper portion may 45 be of any suitable form and is shown as provided with a raised beveled marginal sealing portion 4 which is compressed when the heel is applied and seals the edge point. The heel is secured by nails or other securing 50 means inserted through the holes 5 and washers 6, as is usual.

At its back and to one side of its center line the heel is provided with a downwardly extending projection or extension 7 of any desired shape in plan view above which is 55 a generally similarly shaped recess or cavity 8 in the upper portion of the heel. This arrangement provides a sealed top chamber between the rubber heel and the heel lift above it and forms a pneumatic cushion to 60 soften the blow of impact with the pavement. Ordinarily this cushion would be subjected to an increased wearing effect due to its projection from the bottom of the heel, but undue wear is prevented by a wear 65 resisting element or member 9 of special form which is embedded or inserted in the heel body during its manufacture. This member is shown in detail in Figs. 4 and 5. It 70 comprises a wear receiving body portion 75 10 connected by a short offset neck 11 to an anchor portion 12. The body and anchor portions, speaking generally, are both of oval or oblong form and may be of the same size and general shape if desired. As illustrated in Fig. 1 the body portion is slightly 80 larger than the anchor portion and the two portions are offset by the neck 11 so that they lie in different planes. When the insert is molded into the heel the wear resisting 85 body portion is therefore fully exposed at the surface while the anchor portion is deeply buried in the material of the heel and with the neck is wholly surrounded by 90 said material and solidly anchored in place 95 therein. Either or both portions may be further provided with one or more notches or recesses in their edges such as shown 100 at 13, some or all of which may become filled with the resilient heel material to further 105 anchor the parts and prevent twisting. Two of these recesses in the body portion are utilized for locating the wear resisting member in the mold while forming the heel, said recesses being caused to register with and receive small pins in the mold as is usual. These pins therefore leave the small holes 14 in the resilient material, the hole 15 being formed by a third pin which supports the anchor portion above the mold bottom so 110 the rubber will flow beneath it.

The peculiar form of the wear resisting member enables it to be cheaply manufac-

tured and built into the heel. For example it may be made of metal and cut or punched from a metal sheet. Fig. 6 illustrates one arrangement wherein a series of these metal members are formed from a single sheet of metal, the several members being in nested relation to avoid waste of metal. The possibility of thus cheaply forming this part makes it desirable in some cases to make the two portions of the wear resisting member of the same size and shape.

As shown in Fig. 1 the anchor portion of the member 9 at each end extends beyond the boundaries of the projection from the heel bottom. This arrangement is not necessary as the member 9 will be made in several sizes for different heels and may be proportioned in any manner with regard to the size of the heel recess and projection. For the same purpose, as shown in Fig. 2, the body portion of the wear-resisting member 9 may extend radially outwardly toward the edge of the heel beyond the outer edge of the recess or cavity 8, so that both the body and the anchor portions of the metal insert are in part backed by a solid part of the rubber above them. As a consequence the metal insert is not pushed upwardly when the heel strikes the ground but is held down to receive the wearing effect. At the same time some cushioning effect is retained. However when the latter arrangement is used a part of the blow of impact is imparted to the solid heel body which tends to slightly reduce the cushioning effect and to some extent increases the life of the heel.

The cushioning arrangement does away with the objectionable click which metal parts solidly embedded in a heel produce on impact with the pavement, and the entire construction provides a durable heel at low cost.

What I claim is:

1. A resilient heel having a body portion provided with an upper cushioning chamber and a wear resisting member embedded in said body portion below said chamber and provided with body and anchor portions lying in different planes, said member extending horizontally beyond the edges of said chamber.

2. A resilient heel, comprising a body portion provided with a downwardly extending projection and above the same with a cushioning recess, and an insert having a body portion exposed at the lower surface of said projection and an anchor portion above and to one side thereof, said insert body portion extending horizontally beyond the edges of said recess.

3. A resilient heel, comprising a body portion provided with a downwardly extending projection and above the same with a cushioning recess, and an insert having a body portion exposed at the lower surface of said projection and an anchor portion lying in a plane above said insert body portion, said anchor portion extending horizontally beyond the edges of said recess.

In testimony whereof I affix my signature.

GEORGE N. DAMON.
